[57] **CLAIM**

The ornamental design for multi-positionable drop light cage assembly, as shown and described.

DESCRIPTION

FIG. 1 is a perspective view of a multipositionable drop light cage assembly;

FIG. 2 is a front elevational view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a perspective view of the multipositionable drop light cage assembly in use the broken lines being shown for illustrative purposes only and forming no part of the claimed design.
